DRAFTSMAN'S INSTRUMENT

Carl R. Wern, 13725 Dexter, Apt. 219, Detroit, Mich.

Filed Mar. 18, 1960, Ser. No. 59,784

Term of patent 14 years

(Cl. D52—6)

I claim:

The ornamental design for a draftsman's instrument, as shown.
